UNITED STATES PATENT OFFICE.

FREDERICK C. HOLSTEIN, OF HERMAN, NEBRASKA.

FLOODGATE LATCH.

Application filed September 17, 1924. Serial No. 738,150.

The invention relates to flood gates, and has for its object to provide a device of this character which is normally vertically disposed transversely of a stream, and disposed there-in, and suspended in a manner whereby it will float on the water during the passing of a flood, and after the passing of a flood, will return by gravity to normal operative position.

A further object is to provide the lower end 10 of the gate with a horizontally disposed hinged plate normally held downwardly at its free end by means of a coiled spring, and which plate is provided with a transversely disposed groove for the reception of the detent roller carried by a member imbedded in the bed of the stream.

A further object is to suspend the gate from upwardly extending cables, the upper ends of which are connected to horizontally disposed 20 sleeves, through which a supporting cable extends, and to which a bracing cable is connected, thereby positively supporting the gate.

With the above and other objects in view the invention resides in the combination and 25 arrangement of parts as hereinafter set forth, shown in the drawing, described and claimed, it being understood that changes in the precise embodiment of the invention may be made within the scope of what is claimed without 30 departing from the spirit of the invention.

In the drawing:—

Figure 1 is a vertical transverse sectional view through a stream bed, showing the gate suspended therein.

Figure 2 is a detail perspective view of a portion of the lower end of the gate, showing the hinged latching plate.

Figure 3 is a detail perspective view of one of the supporting sleeves.

Figure 4 is a perspective view of the latching element carried by a member imbedded in the bottom of the stream.

Referring to the drawing, the numeral 1 designates posts as opposite sides of the stream, 45 which posts are braced by the wires 2, which connect the posts to the stakes 3. Extending across the stream bed 4 in a horizontal plane and connecting the posts 1 is a cable 5, on which cable are rotatably mounted, as well as 50 slidably mounted, sleeves 6. Sleeves 6 have connected thereto as at 7 downwardly extending cables 8, which cables have their lower ends connected to the U-shaped gate 9 and support said gate normally in a vertical posi-

tion in the stream bed 4, with its portion 10 55 horizontally disposed and its wings 11 extending upwardly and outwardly adjacent the sides of the stream bed, thereby substantially closing the stream bed, preventing passage of cattle and the like.

Hingedly connected at 12 to the downwardly extending U-shaped member 13, carried by the lower end of the gate is a horizontally disposed relatively wide latching plate 14, which latching plate, adjacent its free end 15 is provided, on its underside, with a transversely disposed groove 16, which groove, when the gate is in normal vertical position receives the detent roller 17 carried by the U-shaped member 18, which extends upwardly from an anchoring log 19, and prevents the gate from moving to a horizontal or floating position, under normal conditions. The detent plate 14, at its free end 15 is provided with an upwardly extending threaded rod 20, 65 which extends through the aperture 21 in the bar 22, secured to the gate, and has surrounding the same, between the bar 22 and the latching plate 14 a coiled spring 24, which normally forces the latching plate 14 downwardly 70 for maintaining the same in close yielding engagement with the detent roller 17. Spring 24 has sufficient tension for maintaining the gate in normal vertical position during the natural flow of water through the stream bed, 75 however in case of flood, where the current is relatively strong and considerable débris is carried down the stream, which will collect against a stationary gate and form a resistance which would result in diverting the 80 stream or breaking the gate, the gate 9 will unlatch and float, thereby allowing the débris to float with the current and prevent damage to the gate. As soon as the flood condition is over the gate 9 will return to normal vertical position by gravity, and the free end 15 of the latching plate will engage the detent roller 17, and the roller 17 will be received in the transverse groove 16 of the latching plate, and the gate will be maintained in normal 85 position by the spring action 24.

To further brace and support the device a cable 25 is provided, which connects the sleeves 6 and the posts 1, thereby positively supporting the device. By making the latching plate 14 relatively wide, it is obvious that any variation and position of the roller will be taken care of or variation in the position

of the gate in a vertical transverse plane, consequently a positive latching is insured at all times.

The invention having been set forth what is claimed as new and useful is:—

A latching device for the lower free end of a horizontally pivoted floor gate, said latching device comprising a horizontally disposed hinged latching plate having a transverse groove in its under side, a guide rod carried by said latching plate, a coiled spring supporting said guide rod and normally forcing said plate downwardly, a detent roller with

which said latching plate cooperates whereby it will be disposed in the groove when the gate is in a vertical position, said detent roller being fixed beneath the gate, said hinged latching plate being relatively wide in relation to the width of the roller and having its groove extending across the same and forming means whereby upon sagging of the gate at either end, the latching device will not be rendered inoperative.

In testimony whereof I hereunto affix my signature.

FREDERICK C. HOLSTEIN.
